(57) **CLAIM**

The ornamental design for a cosmetic container for cosmetic samples for testing, as shown and described.

DESCRIPTION

The patent or application file contains at least one drawing executed in color. Copies of this patent or patent application publication with color drawing(s) will be provided by the Office upon request and payment of the necessary fee.

1. Cosmetic container for cosmetic samples for testing
2. Cosmetic container for cosmetic samples for testing
The reproductions illustrate a cosmetic container for cosmetic samples for testing as a two-part container including a container body and a screw cap; the reproductions include views of the cosmetic container for cosmetic samples for testing with the container body and the screw cap in an assembled state and views of the container body and the screw cap individually; 1.1 shows a perspective view of the cosmetic container for cosmetic samples for testing including a container body and a screw cap in an assembled state; 1.2 shows a side view thereof in the assembled state; 1.3 shows a perspective view of the container body thereof; 1.4 shows a side view of the container body thereof; 1.5 shows a top view thereof in the assembled state; 1.6 shows a perspective view of the screw cap thereof; 1.7 shows a bottom view thereof in the assembled state; 2.1 shows a perspective view of a cosmetic container for cosmetic samples for testing including a container body and a screw cap in an assembled state; 2.2 shows a side view thereof in the assembled state; 2.3 and 2.4 show perspective views of the container body thereof; 2.5 and 2.6 show perspective views of the screw cap thereof; 2.7 shows a perspective view of the container body thereof; in reproductions 2.1-2.7, the blue background and shadows do not form part of the claimed design. The dashed lines depict portions of the
